UNITED STATES PATENT OFFICE.

FRANK E. LONAS, OF NEW YORK, AND HOWARD E. THOMPSON, OF BROOKLYN,
NEW YORK.

CARBURETOR.

Application filed March 1, 1922. Serial No. 540,117.

This invention relates to vacuum or self-feeding carburetors, its principal object being to provide a simple device which will draw fuel from a lower level reservoir and supply to a variable speed internal combustion engine a substantially unvarying ratio of liquid fuel to air in varying quantities.

This object is attained by controlling the admission of all air and fuel to the carburetor by a combined air and fuel valve, the weight of which, acting in opposition to the engine suction converts the widely varying vacuum in the engine manifold due to varying throttle openings, loads and speeds, into an unvarying vacuum in the mixing and fuel chambers of the carburetor, causing fuel to flow thereto through a pipe from a lower level reservoir by reason of the pressure of the atmosphere upon the surface of the fuel therein.

A further object is to provide two passages opening into the mixing chamber of the carburetor, and in communication with the fuel chamber thereof, having a float actuated valve in the fuel chamber cooperating with one of said passages to control the suction effective in said fuel chamber, and to maintain a substantially fixed level of fuel in the fuel chamber; and with these and other objects in view, the invention consists in a device of the class and for the purpose specified, which is simple in construction, efficient in use, and which is constructed as hereinafter described and claimed.

The invention is fully disclosed in the following specification, of which the accompanying drawing forms a part, in which the separate parts of our improvement are designated by suitable reference characters in each of the views, and in which:

Fig. 1 is a transverse vertical section through a carburetor made according to our invention with the parts in their normal or inoperative position;

Fig. 2 a partial section on the line 2—2 of Fig. 1;

Fig. 3 a view similar to Fig. 1 but showing only a detail of the construction on an enlarged scale with parts in a different position;

Fig. 4 a view similar to Fig. 1 but showing a modified form of carburetor;

Fig. 5 a partial section on the line 5—5 of Fig. 6; and,

Fig. 6 a view similar to Fig. 4 but showing

only a detail of the construction and on an enlarged scale with parts in a different position.

In Figs. 1 to 3 inclusive, we have shown one form of our improved carburetor and in said figures 10 represents the main casing or body of the carburetor provided at the top with the usual flange 11 and discharge port controlled by a butterfly valve 12, and adjacent to the bottom of the casing and at one side thereof is an air inlet 13 with which a hot air connection is preferably connected.

Detachably mounted in connection with the bottom of the casing 10, which is slightly enlarged as shown at 14, is a supplemental casing 15 provided with an enlarged base portion 16 having a removable cap 17 at the bottom thereof which, with said enlarged portion, forms a fuel chamber 18 having a fuel admission port 19. The top of the supplemental casing is reduced as shown at 20 and is provided at the top thereof with a tubular extension 21 into which a plug 22 is placed, said plug being secured into the reduced portion 20 as shown at 23. Above the threaded portion 23 of the plug is a slightly enlarged neck portion 24 which forms a fuel passage 25 between the plug 22 and the top face of the reduced portion 20. The transverse dimensions of the plug 22 are slightly less than that of the sleeve extension 21 forming an annular fuel discharge passage 26, which opens outwardly into the mixing chamber 27 of the carburetor through a plurality of fine and closely arranged discharge ports formed by a knurling 28 on the plug 22 at the top of the fuel discharge passage 26.

The plug 22 is provided with a central bore 29 in which a valve needle or rod 30 is adapted to be mounted, said rod being preferably of the same diameter throughout and provided with a head 31 which is mounted in a spider 32 carried by a tubular weighted valve 33 and held therein by a nut 34.

The valve 33 is tubular in form and the central body 32 is joined thereto or formed in connection therewith by a web structure 32^a so that as the valve 33 moves upwardly and downwardly in the casing 10, the valve needle or rod 30 will be correspondingly moved in the bore 29.

Adjustably mounted in connection with the cap 17 is a tubular valve seat 35, which extends into an enlargement 36 of the bore 29 of

plug 22 and fits snugly therein to prevent fuel from leaking upwardly around the sleeve portion of the device 35. The upper end of the bore 35^a is tapered as shown at 37, the 5 length of said taper being equivalent to the extreme movement of the valve needle 30, or approximately so, and when the parts are in the position shown in Fig. 1 the valve needle 30 closes or practically closes the passage 35^a. 10 Extending radially from the top of the enlarged portion 36 of the bore 29 are a plurality of radial fuel discharge ports 38 which form a communication between the enlargement 36 of said bore and the fuel passage 25. 15 The bottom of the bore 35^a is placed in communication with the fuel chamber 18 near the bottom thereof by a plurality of radial ports 39 which are preferably located below a fuel strainer 40 mounted on the cap 17, as clearly 20 shown in Fig. 1 of the drawing. The fuel controlling device 35 may be adjusted by grasping a large milled head 41 at the lower end thereof and turning same to the desired position where it may be held by a lock nut 25 42. The plug 22 extends downwardly into the top of the fuel chamber 18, as shown at 43, and is provided with a tapered seat 44. A plurality of bores 45 extend from the approximate center of said seat upwardly through 30 the plug, as clearly shown in Fig. 1, and four of these bores are preferably employed. The combined area of said bores is sufficient to maintain under all operating conditions of the carburetor, a substantially fixed level of 35 fuel in the fuel chamber. Cooperating with the seat 44 is a tapered valve 46 carried by a float 47 mounted in the fuel chamber 18, and said float is guided by and slidably movable on the fuel controlling device 35, as clearly 40 shown in Fig. 1.

Surrounding the extension 43 and spaced therefrom is an upwardly directed tubular member 48 carried by the float 47, which serves to prevent any possible chance of fuel 45 passing upwardly through the bores 45 between the valve 46 and seat 44 in the event of the fuel raising momentarily above a predetermined level which will be fixed by the operation of said float.

50 In the construction shown in Fig. 1, the valve 33 seats upon the top of the tubular extension 21 as shown at 49, and below this point the valve is tapered or flared outwardly as shown at 50 so as to control the admission 55 of air to the mixing chamber as said valve rises in the casing 10. As the valve rises the valve needle 30 is correspondingly raised and cooperates with the tapered bore 37 of the fuel controlling device 35 to permit the 60 passage of an amount of fuel proportionate to the air as will be apparent.

In Fig. 1 of the drawing, the various parts of our improvement are shown in an inoperative position and, if the butterfly valve 12 is 65 slightly open and the engine started in the

usual manner, fuel will be drawn into the valve chamber 18 through the admission port 19 from a fuel tank or reservoir at a lower level by the suction through the bores 45 as well as through the tapered bore 37, and as 70 the fuel rises in the fuel chamber 18 the float 47 is gradually raised and the valve 46 thereon will gradually close the passage leading to the bores 45, and this operation will continue until the valve 46 is seated, or approximately seated to close or shut off the suction through the bores 45. 75

It will be apparent that at a predetermined instant during the above described operation fuel will be drawn from the fuel chamber 18 80 through the ports 39, the bore 35^a, through the tapered bore 37 around the valve needle 30 out through the fuel discharge passage 26 and discharged into the mixing chamber 27 through the fine openings formed by the 85 knurling 28, and a proportionate amount of air will be drawn into said mixing chamber through the air port formed by the taper 50 of the valve 33.

In the operation of our carburetor the float 90 47 and valve 46 will assume a position which will leave open sufficient suction passage area to replenish the fuel as fast as discharged from the fuel chamber into the mixing chamber, and thus maintain a substantially un- 95 changing fuel level in the fuel chamber. In case of a suddenly increased opening of the throttle causing a drop in the fuel level the drop of the valve 46 away from its seat will 100 instantly increase the suction area between them, and a corresponding increase of fuel flow will restore and maintain the necessary level of fuel in the fuel chamber to supply the increased quantity of fuel required by such increased throttle opening. Thus the 105 float and valve will fluctuate within very narrow limits of vertical movement and at all times maintain just sufficient suction opening to supply fuel as fast as discharged from the fuel to the mixing chamber. 110

In other words, the float 47 and the valve 46 thereon will fluctuate slightly to at all times compensate for and maintain a substantially fixed fuel level in the fuel chamber 18 to meet the varying requirements of the motor. With 115 a carburetor of this construction, at all times, and regardless of the level of fuel in the fuel storage tank, and regardless of the operating conditions of the vehicle, whether traveling on a level road-way or a grade, the operative 120 parts of the carburetor and mainly the valve 46 and float 47 will automatically operate to control the exposed suction area to maintain under the aforesaid conditions a substantially fixed level in the fuel chamber of the carburetor; in other words, under all operating 125 conditions the fuel is drawn into the mixing chamber 27 of the carburetor from a substantially fixed fuel level in the fuel chamber 18.

In the above described operation, it will be 130

understood that the increased velocity of flow of air past the fuel discharge, which is produced by the tapered face of the valve forming a Venturi throat, creates a greater depression at the fuel discharge, causing the fuel to be lifted from the fuel chamber notwithstanding the suction action which takes place in the suction passages opening into said fuel chamber.

10 In the construction shown in Figs. 4 to 6 inclusive, we have shown a slight modification in the general design of the carburetor and in Fig. 4, it will be noted that the supplemental casing 15, or the base thereof, fits within 15 and is removable from the base of the main casing 10 as shown at 51, and the cap 17 is omitted and substituted therefor is a cup-shaped casing 52 in which the fuel chamber 18 is formed.

20 It will also be noted that a sleeve 53 is mounted in the top portion of the casing 10 and extends downwardly into the mixing chamber and operates in connection with the valve 33 to form a dash-pot 54 for said valve, 25 and also serves to maintain a substantially fixed area through the carburetor and avoids the expansion of the fuel mixture above the valve which would be the case in the construction shown in Fig. 1.

30 In Figs. 4 to 6 inclusive, the adjustable fuel controlling device 35 also is omitted, and in said figures, we provide a sleeve extension 55 to the valve 46 on the float 47. This sleeve extension, or the bore thereof, is tapered at the 35 upper end as shown at 56, and the valve needle 30 operates in connection with the tapered bore 56 to control the fuel as it passes therethrough. The sleeve extension 55 is provided in the periphery thereof with a plurality of flutes 57 which form between said sleeve and the enlargement 36 in the bore 29 suction passages, controlled by the valve 46 on the float operating in connection with the beveled seat 44 as in the construction 45 shown in Fig. 1.

In the construction shown in Figs. 4 to 6 inclusive, it will be apparent that the suction passages 57 as well as the fuel passage lead to a common discharge or opening into the 50 mixing chamber instead of through two independent openings or discharges as in Figs. 1 to 3 inclusive, but the operation of the construction shown in Figs. 4 to 6 inclusive will be precisely the same as that shown in 55 Figs. 1 to 3 inclusive, the only difference being that as the float 47 and valve 46 rise the flutes or suction passages 57 are gradually reduced in area or finally sealed by the operation of the valve 46 in connection with the 60 seat 44.

In both forms of construction where the valve needle 30 passes through the central body 32 of the valve 33 a slight clearance is provided to facilitate the self-alinement of 65 said valve needle in the bore 29 thus provid-

ing for a free action of the valve 33 at all times avoiding any possibility of sticking thereof.

It will also be apparent that while we have shown the fuel chamber as incorporated in, or 70 contained within, the general structure of the carburetor that the fuel chamber may be independent of the carburetor casing, or be located externally thereof as is a common custom in the art to which this invention relates, 75 and while we have shown in the accompanying drawings certain details of construction for carrying our invention into effect, it will be understood that we are not necessarily limited to these details, and various changes 80 therein and modifications thereof may be made, within the scope of the appended claims, without departing from the spirit of our invention or sacrificing its advantages.

Having fully described our invention, what 85 we claim as new and desire to secure by Letters Patent, is:—

1. In a carburetor having a member operated by the engine suction for maintaining a substantially constant depression at the 90 fuel discharge into the mixing chamber of the carburetor, a fuel chamber below said fuel discharge, said member including means controlling the transmission of fuel from the fuel chamber to said fuel discharge, means 95 including a float actuated valve and a port controlled by said valve for placing the fuel chamber in communication with the mixing chamber, whereby fuel may be drawn from a reservoir at a lower level to said fuel chamber 100 to maintain a substantially fixed fuel level in said fuel chamber below said fuel discharge.

2. In a carburetor having a member operated by the engine suction for maintaining a substantially constant depression at the 105 fuel discharge into the mixing chamber of the carburetor, a fuel chamber below said fuel discharge, said member including means controlling the transmission of fuel from the fuel chamber to said fuel discharge, means including a float actuated valve and a port controlled by said valve for placing the fuel chamber in communication with the mixing chamber, whereby fuel may be drawn from a reservoir at a lower level to said fuel chamber 110 to maintain a substantially fixed fuel level in said fuel chamber below said fuel discharge, said member and second named means cooperating to provide a supply to the mixing chamber of an unvarying mixture of 115 fuel and air.

3. A suction feed carburetor comprising a fuel chamber, a mixing chamber positioned entirely above the fuel chamber, a suction passage placing said chambers in communication, a fuel discharge opening into the mixing chamber and in communication with said fuel chamber, a combined air and fuel valve operated by engine suction for supplying an unvarying ratio of fuel and air to the mix- 120

ing chamber and for creating a depression in said suction passage to raise fuel from a fuel storage at a lower level to said fuel chamber and maintaining a substantially fixed level in said chamber by the action of said automatically operated means.

4. In a vacuum feed carburetor having a mixing chamber and a fuel chamber below the mixing chamber, independent passages placing said chambers in communication, one of said passages constituting a fuel discharge passage and opening into the mixing chamber at a point below the other passage, the first named passage opening into the lower end 10 portion of the fuel chamber and the second named passage opening into the upper end of said chamber, a member operated by the suction of the engine controlling the admission of air to the mixing chamber and the passage 15 of fuel from the fuel chamber into the mixing chamber through said first named passage, and means involving an automatically operated valve for controlling the second named passage for regulating the transmission of fuel from a fuel storage tank at a lower level 20 to the mixing chamber of the carburetor and for maintaining a substantially fixed-level of fuel in said fuel chamber at a point below 25 the communication of the second named passage with said fuel chamber.

5. A carburetor having mixing and fuel chambers placed in communication by a suction passage, the fuel chamber being positioned below the mixing chamber, means for maintaining a substantially unvarying vacuum in the mixing chamber, whereby fuel may be drawn from a fuel storage at a lower level 30 to the fuel chamber and supplied to said mixing chamber, a float actuated valve in the fuel chamber controlling said suction passage to maintain a substantially constant level of fuel in the fuel chamber, and a fuel discharge 35 passage opening into the lower end portion of the fuel chamber and into said mixing 40 chamber.

chamber whereby fuel may be supplied to the mixing chamber in the operation of said first named means.

6. A carburetor having mixing and fuel chambers placed in communication by a suction passage, the fuel chamber being positioned below the mixing chamber, means for maintaining a substantially unvarying vacuum in the mixing chamber, whereby fuel may be drawn from a fuel storage at a lower level 45 to the fuel chamber and supplied to said mixing chamber, a float actuated valve in the fuel chamber controlling said suction passage to maintain a substantially constant level of fuel in the fuel chamber, a fuel discharge passage opening into the lower end portion of the fuel chamber and into said mixing chamber whereby fuel may be supplied to the mixing chamber in the operation of said first named means, and said suction passage opening into the upper end of the fuel chamber 50 at a point above the level of fuel maintained therein.

7. In a carburetor having a fuel chamber positioned below the fuel discharge into the mixing chamber of the carburetor, means for placing the fuel discharge in communication with said fuel chamber, a suction passage exposed to the mixing chamber and opening into the upper end of said fuel chamber above the level of fuel therein, a float actuated valve 55 in the fuel chamber and cooperating with said suction passage to maintain a substantially fixed fuel level in said fuel chamber and below said fuel discharge, and a valve movable relatively to said fuel discharge to create a 60 depression at the fuel discharge to lift fuel from said chamber for supply to the mixing chamber of the carburetor.

In testimony that we claim the foregoing as our invention, we have signed our names, 65 this 28th day of February, 1922.

FRANK E. LONAS.
HOWARD E. THOMPSON.
